THUNDER AND LIGHTNING SCENE

The thunder and lightning scene as shown on the accurate wall portion 58 of the drum 24 is constructed to simulate a thunder cloud, sky scene with lightning behind the cloud, and rain falling from the cloud.

The accurate wall portion 58 has four-sided box member 61 positioned on the outside of the wall portion 58 and held in position by a pair of magnets 62 and 63. The magnet 62 is fixed to the outside 58' of the accurate wall portion 58, and the magnet 63 is fixed to the inside of the base panel 64 of the box 61. The magnets are magnetized to attract one another when in their position illustrated in FIGS. 1 and 2, whereby they abut one another and thereby hold the box 61 in place on the wall portion 58 as illustrated in FIGS. 1 and 2.

The box 61 has four side walls 65, 65', 65" and 65''' which surround the base panel 64 and are integrally connected thereto. The base panel 64 has a pair of zigzag openings 66 and 67, each of which have a jagged three-like appearance and extend downward along the base panel 64 and each of which simulate, in their outline, lightning flashes or lightning bolts. Electric bulbs 68 and 69 are mounted behind the slots 66 and 67, respectively, and when the light bulbs 68 and 69 are illuminated, the light emanating from the bulbs passes through the slots 66 and 67 to give the appearance of lightning bolts striking in the sky.

A wad of cotton 70 surrounds the box 61, to give the appearance of a cloud. When the bulbs 68 and 69 are illuminated, it further gives the appearance that lightning is striking behind the clouds.

The outside surface 58' of the area of the wall portion 58 adjacent the clouds formed by the cotton 70 is painted a grayed blue to simulate stormy skies.

A wall 71 divides the box 61 into two compartments, one for each lightning bolt slot 66 and 67, so that when one bulb 68 or the other bulb 69, is illuminated, its rays will pass through its respective slot 66 or 67. The wall 71 extends down from the top wall 65''' to the adjacent top of the magnets 62 and 63 and terminates, and then extends from adjacent the bottom of the magnets 62 and 63 to the bottom wall 65' to thereby divide the box into two compartments. The side walls 65, 65', 65" and 65''', center panel 64, and dividing wall 71, are all made of opaque material so that light will not pass through except through the slots 66 and 67.

The rain scene beneath the box 61 and cotton wad 70, is provided by a plurality of slit-like openings 51' in the accurate wall portion 58, which run in vertical rows spaced from one another, beneath the cotton cloud 70. The perforated disc 49 rotated counter-clockwise and when viewed from FIG. 1, so that the left portion of the perforated disc as it passes through the light from the bulb 50 creates a downward like movement of the light rays as they reach the slits 51' so as to simulate rainfall.

NIGHTTIME SCENE

The accurate wall portion 59 of the drum 24 simulates a nighttime sky scene after the storm has cleared, which storm was simulated by accurate wall portion 58. The nighttime scene of wall portion 59 simulates clear skies with stars shining and a quarter moon shining in the sky.

The accurate wall portion 59 has a plurality of small dot-like perforations or openings 96, and an opening 97 which has the outline of a quarter moon, to simulate stars and a quarter moon respectively. Behind the wall portion 59 is a curved and concave wall 98 having its outer ends 98' and 98'' fixed to the inside of the wall portion. The concave wall 98 has reflective material along its inner face 99. A light bulb 100 is mounted between the wall portion 59 and the concave wall 98 and when illuminated its light rays pass and are reflected by the reflective material and pass out through the dot-like openings 96 and the moon-like opening 97 to give the simulated night-time appear-

ance of the stars and moon shining, when viewing the accurate portion 59 from its outer face 59'.

The wall portions of accurate portion 57 adjacent the opening 96 and 97 are painted blue to give the appearance of a clear blue sky.

DAYTIME SCENE

The accurate portion 60 of the drum 24 simulates a daytime scene. The accurate portion 60 is painted a light blue and an electric bulb 101 is mounted in the drum 24 above the accurate portion 60 and when illuminated gives the appearance of sunlight in the sky. A switch 102 is mounted to the cover 22' in the path of block 73, and is engaged by the block 73, when the daytime scene approaches the window area and is held on by the block until the daytime scene passes the window area.

A semi-circular base block 122 is mounted to the toy plate 21''' and surrounds the drum in spaced relation about its lower edges. The blocks have an irregular top surface 127 which is painted green and brown to simulate the ground or earth.

OPERATION

25 The rotary toy invention 20 operates as follows:

The closing of the main switch 103 energizes the motor 34. Assuming for purposes of illustration that the drum 24 is positioned with the nighttime scene 59 generally facing the open window as illustrated in FIGS. 3 and 4, the motor 34 through its output gear 34 rotates the drum from left to right as viewed from FIGS. 3 and 5, or counter clockwise as viewed from FIG. 6 in slow motion.

35 Mounted to the top of the drum 24, on the edge of the drum generally opposite the thunder and lightning scene is an accurate block 73 which serves as an electric contact system for the thunder and lightning simulation of the thunder and lightning scene on accurate portion 58.

40 The block 73 has radial legs 74 and 75 fixed at their one ends to the block 73 and their other ends to the drum 24, to attach the block to the drum. A magnetic reproducing head 76 is fixed to the outer top wall portion 77 of the cover 22' at the housing 22. A pair of switches 78 and 79 are mounted beneath the magnetic head. The magnetic head 76, and the switches 78 and 79 are in alignment with three horizontal tracks on elongated outer surface portions 80, 81, and 82, on the accurate outside surface of the block 73.

45 The tracks 80, 81 and 82 are divided into separate areas, 84, 85, 86, 87, 88, 89, 90, 91, and 92, which represent time intervals and govern the time sequence of activation of the light bulbs 68 and 69, which are controlled by switches 78 and 79, and the magnetic tape strips 93 on the track 80, are pre-recorded magnetically with the sound of thunder, and when the magnetic head then engages these tape strips as the accurate block goes by the sound of thunder is reproduced through the magnetic head.

50 The track 81 has lobs or ridges 94 at intervals along the nine separate areas, and when the switch 78 reaches these lobs or ridges, the track engages the switches 78 momentarily and activates the light bulb 68 giving the appearance of lightning striking.

55 The track 82 has lobs or ridges 95 at intervals along its nine separate areas, and when the switch 79 reaches these lobs or ridges, the lobs or ridges 95 will engage the switch 79 momentarily and activate light bulb 69 giving the appearance of a lightning bolt striking.

60 The turning of the main switch also illuminates the light bulb 100 which is activated by the main switch 103, and causes light to pass through the openings 96 and 97 in the drum, and simulates a nighttime scene with the stars and a quarter moon showing. The lobs 94 and 95 have varying horizontal lengths so as to vary the length

of time the bulbs 68 and 69 are illuminated, by varying the length of time the switches 78 and 79 are held closed by the lobs 94 and 95.

When the cloud 70 or the drum has reached its position shown in dashed lines and designated by numeral 104, the block member 73 will accordingly have reached the point also shown in dashed lines and designated by numeral 105 and the daytime sky scene will be coming into view in front of the window area 23. At this point the control arm 102' of the conventional variable resistor 102 will be rotated by the pin 102''. The variable resistor 102 being mounted on the block member 73 and the pin 102'' being fixed to the underside 22'' of the cover 22' of the housing. The pin 102'' engaging the L-shaped control arm 37 of the variable resistor gradually pivots the arm 37 counter-clockwise from its position shown in solid lines and designated by numeral 38 to its position shown in dashed lines and designated by numeral 39, which gradually decreases the resistance in the line and gradually illuminates the bulb 101. The bulb 101 will remain illuminated during the time the daytime scene passes in front of the window area 23 and until the arm 37 engages the pin 40, which pin is also fixed to the underside 102'' of the cover 22'. When the arm 37 engages the pin 40, this pivots the arm 37 gradually clockwise back to its position shown in solid line, and gradually decreases the illumination of bulb 101 and turns it off.

When the cloud 70 reaches the position relative to the housing 22, as shown in dashed lines in FIG. 2, and designated by numeral 106, the first area 84 of block member 73 will begin traveling past the switches 78 and 79 and magnet head 76, and the cloud 70, will be approaching the window over from left to right when viewed from FIG. 1.

As the first area is reached the ridge 94 in area 84 of track 81 will activate the bulb 68, and illuminate through zigzag opening 66, and through the cotton cloud 70, giving the appearance of a lightning bolt striking. The bulb 68 will only be activated momentarily, and then deactivated after the ridge has passed.

As the drum 24 continues to rotate and area 85 comes into vertical alignment with the magnetic heads and switches, the ridge 95 in track 82 will activate bulb 69 and illuminate through zigzag opening 67 and through cloud 70, giving the appearance of a lightning bolt striking. The bulb 69 will also only be activated momentarily and deactivated after the ridge has passed.

When the area 86 comes into vertical alignment the ridge 94 in track 81 will again activate switch 78 illuminating bulb 68, giving the appearance of a lightning bolt striking. As the area 86 passes across the magnetic head, the magnetic strip 93, will engage magnetic head 76, shortly after bulb 68 was illuminated and the said reproduction strip will produce the sound of thunder, for most of the area 86.

When the area 87 comes into alignment the ridge 95 will through, switch 79, again activate bulb 69, giving the appearance of a lightning bolt striking. Again as area 87 passes across the magnetic head 76, the magnetic strip 93 in area 87 will engage the magnetic and reproduce the sound of thunder.

As areas 88, 89, 90, 91, and 92 are reached the same process as occurred in areas 86 and 87 will repeat itself, with the bulbs 68 and 69 alternately activating as the area is reached and the sound of thunder following as the area passes by the magnetic heads.

The thunder sound will be delayed long after the bulbs are illuminated, as the storm cloud approaches the window area, since in normal circumstances the lightning and the corresponding thunder are separated more in time as a storm cloud approaches, as it takes longer for the sound to reach the ears of the person that it does the lightning flash. Also, the interval between the simulated lightning flashes and the simulated thunder is close as the storm

cloud comes directly in front of the viewer to correspond with the fact that when a storm cloud is very close or directly over a person the interval between the lightning and thunder is close as practically simultaneous.

After the rear end 83' of the block member 73 has passed by the magnetic switches and they all move across the block member have passed by the switches and magnets, and storm cloud will substantially have a left the window area as viewed from FIG. 1, and the nighttime scene will reappear and the sequence begins all over.

The rain scene will be operating continuously as the rotating disc 49 driven continuously as long as the drum 24 is rotating and the bulb 50 is activated by the closing of the main switch 34. The electrical system provides four rings 107, 108, 109 and 110, made of electric conductive metal which may be fixed coaxially to the underside of the plate 26 and will rotate with the drum 24, while four electrical conductive brushes 112, 113, 114 and 115 are fixed to the top of the panel member 21'' and continuously engage their respective rings 107-110 as the drum rotates to provide a conventional electrical connection through respective circuit wires for electrical current. The operator will continue to repeat it all until the main switch 103 is turned off.

Thus it will be seen that a novel toy device has been provided which simulates a storm scene with lightning, and thunder, and storm clouds, and which also simulates a nighttime and a daytime scene.

It will be obvious that various changes, and departures may be made to the invention without departing from the spirit thereof, and accordingly it is not intended that the invention be limited to that specifically described in the specification or as illustrated in the drawings, but only as set forth in the appended claims wherein:

What is claimed is:

1. A rotary toy device comprising a rotary drum, a housing surrounding said drum, said housing having a window area for viewing the drum, said drum having a horizontal platform with a plurality of pictorial structural members arranged about the circumference of the drum with each structural member forming a scene, one of said structural members having an upright wall painted a grayish blue to simulate stormy skies, a plurality of zig-zag openings in said wall member extending downward along the wall member and each having the silhouette of a flash of lightning, each of said openings having illuminating means behind the opening with a wall member separating one of the illuminating means from another of the illuminating means so that each may operate independently to illuminate their zig-zag opening, a sound track having a simulate sound of thunder, electric means staggering the illumination of the zig-zag openings in relation to the actuation of the sound of thunder to provide a variable delay between the lightning illumination and the thunder activation as the thunder and lightning scene passes in front of the window area to simulate the approach of thunder and lightning to the viewer in front of the window area.

2. A rotary toy device according to claim 1 wherein said scenes on said drum render a night-time scene and a daytime scene following said storm scene.

3. A rotary toy device according to claim 1 wherein said scenes include a rainfall scene.
